CONVERTER CIRCUIT

Edward W. Herold, Verona, N. J., assignor to
 Radio Corporation of America, a corporation
 of Delaware

Application August 10, 1935, Serial No. 35,593

3 Claims. (Cl. 250—20)

My present invention relates to frequency converters adapted for use in signaling systems, and more particularly to a novel and improved type of frequency converter network adapted for use in superheterodyne receivers.

Frequency converter networks of a type utilizing electronic coupling are well known at the present time. One of the types in common usage at the present day employs as a converter tube 10 a device known as a pentagrid converter tube. In such a converter the signal and local oscillation grids are separated by a positive screening grid. The output electrode, or plate, of the converter tube has developed in its circuit the operating intermediate frequency energy. Such converter tubes often have circuits associated therewith, in addition to the usual signal circuits, which render them operative as a composite first detector—local oscillator network. In other arrangements the converter tube of the multi-grid type may be used with an independent local oscillator.

In the past at least two conventional methods of coupling the local oscillator, for example, of the triode type, to a pentagrid mixer tube have been used. In one of these methods, the local oscillator grid of the mixer tube, is maintained at the same direct current and alternating current potentials as the grid of the local oscillator tube. In such a circuit, grid current is drawn by both the converter oscillator grid, and the local oscillator tube grid, and the effect of such grid current flow is to automatically bias these grids by the drop in the grid leak of the local oscillator tube. Accordingly, if the oscillator peak voltage changes, then the direct current bias changes a proportional amount, and, therefore, shifts the working point on the converter oscillator grid characteristic. Since it is found that the highest conversion gain in a pentagrid converter tube results from operation at an oscillation grid direct current bias which is nearly constant, this method of coupling the oscillator tube to the converter tube is not desirable.

A second conventional method of coupling between a local oscillator tube and a converter tube involves the utilization of a separate leak and condenser for the converter oscillation grid. The same condition exists in this case as described above. An additional disadvantage of this second method of conventional coupling results from the possibility of the converter blocking due to secondary emission from the converter oscillation grid.

Accordingly, it may be stated that it is one of

the main objects of the present invention to overcome the disadvantages enumerated heretofore in the coupling of a pentagrid converter tube to a local oscillator tube, and to accomplish this with a novel coupling arrangement involving the 5 direct connection of the local oscillator tube grid and the converter oscillation grid, the direct current bias on the converter oscillation grid being partially fixed by a voltage drop developed in the cathode circuit of the converter tube. 10

Another important object of this invention is to provide a coupling circuit between a converter tube of the pentagrid type and a local oscillator tube wherein the oscillation grid of the converter and the grid of the oscillator tube are 15 directly connected together so that the alternating current voltage on the converter oscillation grid and the local oscillator grid is the same, but wherein the direct current bias on the converter oscillation grid is never less than that 20 due to the voltage drop across the biasing resistor in the converter cathode circuit and wherein the local oscillator grid current supplies an additional bias by the voltage drop in the local oscillator grid leak. 25

Still another object of the invention is to provide a frequency changer network for a superheterodyne receiver, the network being of a type comprising a converter tube of the pentagrid type and a local oscillator, and wherein the coupling circuit between the local oscillator tube grid and the converter oscillation grid is such that the network has substantially a two to one 30 advantage over conventional coupling arrangements when the oscillator voltage is low, and for 35 higher oscillator voltages there is considerably less variation of gain with oscillator voltage.

Other objects of the invention are to improve generally the efficiency of operation of frequency changer networks for superheterodyne receivers, 40 and more especially to provide frequency changer networks which are not only reliable in operation and productive of higher conversion gains than conventional circuits of the same type, but are economically manufactured and assembled 45 in radio receivers.

The novel features which I believe to be characteristic of my invention are set forth in particularity in the appended claims; the invention itself, however, as to both its organization 50 and method of operation will best be understood by reference to the following description taken in connection with the drawing in which I have indicated diagrammatically a circuit organiza- 55

tion whereby my invention may be carried into effect.

In the drawing:

Fig. 1 shows a frequency changer network for 5 a superheterodyne receiver embodying the present invention.

Fig. 2 graphically illustrates the operation of the present invention.

The circuit arrangement shown in Fig. 1 comprises a signal source 1 which is adapted to feed 10 signals of a desired signal frequency range into the tunable input circuit 2 of the first detector network. It is to be understood that the first detector comprises a tube 3 of the so-called pentagrid converter type. The specific type tube 15 shown in the drawing is of the 6L7 type, and is a tube whose electrodes are disposed within a metallic tube envelope. For this reason the envelope of tube 3 in Fig. 1 is shown as grounded. 20 While the construction of tube 3 is not a part of the present invention, it is pointed out that the tube comprises the usual cathode, signal input grid and output plate. The signal grid is connected to the high alternating potential side of 25 the tunable signal input circuit 2, and the cathode is connected to ground through the usual cathode bias resistor R which is shunted by bypass condenser C. As is well known to those skilled in the art, the voltage drop across resistor R furnishes the normal operating bias 30 for the signal grid of tube 3, and the signal grid returns to ground through the conventional AVC (automatic volume control) circuit. It is not believed necessary to show the details of 35 such AVC circuit since those skilled in the art are fully aware of the construction and operation of such a circuit.

It is believed sufficient for the purposes of the present application to point out that for signals 40 of an intensity less than a predetermined value, the voltage drop across resistor R furnishes the sole operating bias for the signal grid. When the signals impressed on circuit 2 increase above that value then the AVC circuit goes into operation 45 and acts to increase the negative bias on the signal grid of tube 3. The condenser C' is connected between the low alternating potential side of input circuit 2 and the cathode side of bias resistor R, and this condenser furnishes 50 a path for the signal currents.

Between the signal grid and plate of tube 3 there are disposed four grids, the third grid from the cathode functioning as the oscillation grid, and the second and fourth grids being maintained 55 at a positive potential of approximately 150 volts, and functioning to electrostatically screen the signal grid from the oscillation grid. The fifth grid is disposed between the fourth, or positive, grid and the output plate, and it 60 will be noted that the fifth grid is connected to the cathode of tube 3 within the tube envelope. The plate of tube 3 may have a positive potential of approximately 250 volts impressed thereon, and the operating intermediate frequency energy is derived from resonant circuit 4 which is connected to the plate. The circuit 4 is coupled to the following resonant circuit 5, the latter also being tuned to the operating intermediate frequency. The networks following circuit 65 5 may comprise one or more stages of intermediate frequency amplification followed by a demodulator, audio network and a reproducer. The AVC rectifier may be the second detector itself, or, if desired, a separate rectifier may be 70 used for this purpose. By way of illustration,

it is pointed out that the automatic volume control circuit shown in Fig. 1 of application Serial No. 29,014, filed June 29, 1935, by Paul F. G. Holst may be used in the receiving system shown in Fig. 1 of the present application.

The signal source 1 which feeds the tunable signal input circuit 2 of the first detector tube 3 may comprise the usual signal collector feeding one or more stages of tunable radio frequency amplification. The local oscillator is a 10 triode whose cathode is connected to the grounded side of the bias resistor R, and between whose control grid and cathode is connected the tunable local oscillation circuit 6. The control grid of oscillator tube 7 is connected to one side of 15 the tunable circuit 6 through the condenser 8, and the grid leak resistor 9 is connected between the cathode and control grid of oscillator tube 7. The oscillation grid 13 of tube 3 is connected by lead 10 to the control grid side of leak resistor 9. 20 The plate of oscillator tube 7 is regeneratively coupled, through coil 11, to the tunable circuit 6, and a positive potential of approximately 150 volts may be applied to the plate of oscillator tube 7.

The dotted lines 12 designate the usual mechanical uni-control device employed to vary the rotors of the variable tuning condensers 2' and 6' of the tunable circuits 2 and 6 respectively.

The locally produced oscillation voltage is impressed on the third grid of converter tube 3, and it will be observed that this oscillation grid 13 and the control grid of oscillator tube 7 are at the same alternating current potential, due to the direct connection 10. In so far as direct 35 current potentials are concerned, the direct current bias on oscillation grid 13 is due to the voltage drop across resistor R, and the voltage drop produced across the leak resistor 9 by the oscillator grid current. Hence, it will be seen that 40 the direct current voltage on the oscillation grid 13 is never less than that due to the voltage drop across bias resistor R. Typical operating voltages for certain of the electrodes of the frequency 45 changer network have been given. The signal grid may be operated with a bias of -6 volts, and a direct current bias of approximately -20 volts may be utilized on the oscillation grid 13. It may be pointed out that the peak oscillator 50 voltage applied to the oscillation grid 13 is approximately 25 volts, and that the conversion conductance is approximately 325 micromhos.

In Fig. 2 is shown graphically the practical significance of the advantage obtained by the use of the present invention over the conventional 55 coupling circuits described heretofore. In Fig. 2 there is shown a comparison between two curves secured by plotting "CONVERSION CONDUCTANCE" against "OSCILLATOR PEAK VOLTS". The dotted line curve shows the curve of conversion conductance against peak oscillator voltage secured by prior converters using typical operating voltages, and this dotted line curve is compared with the full line curve designating the operation of the present invention. It will be observed from 60 Fig. 2 that the converter circuit shown in Fig. 1 has almost a two to one advantage over conventional arrangements when the oscillator voltage is low. For higher oscillator voltages, there is considerably less variation of gain with oscillator voltage when the present circuit is used. This is a decided advantage in receiver design in as much as oscillator voltages commonly vary two to one over the tuning range while it is preferable to keep the gain approximately constant. It will 70 75

now be seen that by virtue of the present invention the local oscillator network is coupled to the converter network in such a manner that the highest conversion gain is secured, and that its efficient operation results because of the maintenance of the direct current bias on the oscillation grid 13 at a value which is nearly constant. It is pointed out that the present coupling arrangement is equally applicable to other types 10 of converter networks wherein a separate oscillator tube is used.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

20 What I claim is:

1. In combination, in a frequency changer network, a mixer tube of the type including a cathode, a signal grid, a plate, an oscillation grid, and means for electrostatically screening the signal grid from the oscillation grid, a local oscillator network including a tube having at least a cathode, control grid and plate, the oscillator plate being regeneratively coupled to the input circuit 25 of the oscillator tube to provide local oscillations, a grid leak resistor connected between the control grid and cathode of the oscillator tube, a direct current connection between the oscillation grid of the mixer tube and the oscillator tube control grid, an impedance in the cathode circuit 30 of said mixer tube for developing a predetermined direct current voltage thereacross from the space current flow therethrough, said leak resistor and impedance being connected in series whereby the bias on said oscillation grid is the sum of said voltage and the direct voltage drop across the leak resistor.

2. In combination, in a frequency changer network, a mixer tube of the type including a cathode, a signal grid, a plate, an oscillation grid, and means for electrostatically screening the signal grid from the oscillation grid, a local oscillator network including a tube having at least a cathode, control grid and plate, the oscillator

plate being regeneratively coupled to the input circuit of the oscillator tube to provide local oscillations, a grid leak resistor connected between the control grid and cathode of the oscillator tube, a direct current connection between the oscillation grid of the mixer tube and the oscillator tube control grid, an impedance in the cathode circuit of said mixer tube for developing a predetermined direct current voltage thereacross from the space current flow therethrough, 10 said leak resistor and impedance being connected in series whereby the bias on said oscillation grid is the sum of said voltage and the direct voltage drop across the leak resistor, and a direct current connection between the signal grid of said 15 mixer tube and the junction of said impedance and leak resistor.

3. In combination, in a frequency changer network, a mixer tube of the type including a cathode, a signal grid, a plate, an oscillation grid, 20 and means for electrostatically screening the signal grid from the oscillation grid, a local oscillator network including a tube having at least a cathode, control grid and plate, the oscillator plate being regeneratively coupled to the input 25 circuit of the oscillator tube to provide local oscillations, a grid leak resistor connected between the control grid and cathode of the oscillator tube, a direct current connection between the oscillation grid of the mixer tube and the oscillator tube control grid side of the leak 30 resistor, an impedance in the cathode circuit of said mixer tube for developing a predetermined direct current voltage thereacross from the space current flow therethrough, said leak resistor and 35 impedance being connected in series whereby the bias on said oscillation grid is the sum of said voltage and the direct voltage drop across the leak resistor, a tunable signal input circuit connected between the signal grid and cathode of 40 the mixer tube, a tunable oscillation circuit connected between the cathode and control grid of the oscillator tube and in shunt with said grid leak resistor, and a condenser connected between one side of said oscillator tube tunable circuit 45 and the oscillator tube control grid.

EDWARD W. HEROLD.
